UNITED STATES PATENT OFFICE.

STEPHEN OBEDA, OF NEW YORK, N. Y.

SELF-ANCHORING SPIKE.

1,199,297.

Specification of Letters Patent. Patented Sept. 26, 1916.

Application filed June 6, 1916. Serial No. 102,028.

To all whom it may concern:

Be it known that I, STEPHEN OBEDA, a subject of the King of Hungary, residing at New York, in the county of New York and 5 State of New York, have invented certain new and useful Improvements in Self-Anchoring Spikes, of which the following is a specification.

This invention relates to certain new 10 and useful improvements in self-anchoring spikes.

The primary object of the invention is the provision of a spike adapted for railroad and similar uses provided with an anchoring 15 means manually engageable and automatically releasable whereby the spike is secured against removal when positioned in the work such as a railway tie.

A further object of the device is to provide 20 a spike having a manually actuated anchoring means automatically locked in position when projected and retracted upon withdrawing the spike after the locking means has been released.

25 A still further object of the device is to provide an anchoring spike that is easy and inexpensive to manufacture and capable of securing the spike in locked seating engagement within the work.

30 With these general objects in view and others that will appear as the nature of the invention is better understood, the same consists in the novel construction, combination and arrangement of parts hereinafter more 35 fully described, illustrated in the accompanying drawings, and then claimed.

In the drawings forming a part of this application and in which like designating characters refer to corresponding parts 40 throughout the several views:—Figure 1 is a side elevation of the spike with the anchoring means closed. Fig. 2 is a central longitudinal sectional view thereof. Fig. 3 is a view similar to Fig. 2 with the spike locked 45 in its anchored position within the work. Fig. 4 is a top plan view of the spike, and, Fig. 5 is a transverse sectional view thereof upon the plane of the anchoring pivots with the anchor members partly extended.

50 The present invention contemplates the provision of a double headed spike 10 of substantially the form of a railroad spike having a squared shaft 11 and a terminal head 12 at one end and a pointed opposite 55 end 13.

The spike 10 is provided with an axial

bore 14 communicating at its lower end with a transverse slot 15 extending across the shank 11 at the point of connection of the pointed end 13 thereof, the slot 15 being 60 substantially V-shaped with downwardly converging opposite sides or faces 16 parallel with the outer converging side faces 17 of the spike point 13.

A cylindrical bar 18 is longitudinally 65 slidably mounted within the bore 14 of the spike and has its inner end provided with oppositely arranged teeth 19 in constant mesh with the teeth 20 upon the substantially semi-circular ends 21 of anchoring 70 arms 22 pivotally mounted within the slot 15 upon transverse pins 23. The arms 22 are normally positioned inwardly of the slot 15 with their free ends in contact with each other and with their outer faces substantially flush with the V-shaped sides of the spike point 13. The upper free end of the bar 18 is arranged slightly above a transverse opening 24 in the spike head 12 when the arms 22 are closed while a bolt 25 is 80 slidably positioned within the opening 24 having a leaf spring 26 carried by the shaft 11 tending to project the bolt 25 inwardly of the bore 14, it being understood that the outer end of the bolt 25 is connected to the 85 spring 26.

With the spike 10 arranged as illustrated in Figs. 1 and 2 of the drawing, the same may be readily driven into the work such as a railway tie 27 until the lower faces 28 of 90 the head 12 engage the upper face 29 of the tie. At such time, the spike being entirely seated in the work, a desirable implement may be inserted in the upper open end of the bore 14 and bar 18 driven downwardly, 95 which action forces the arms 22 outwardly upon their pivots 23, the sharpened outer edges 30 of the arms cutting their way upwardly in arcuate paths through the tie 27. When the bar 18 is depressed with the arms 100 22 fully outstretched, the bolt 25 under the influence of the spring 26 passes inwardly of the bore 14 overlying the upper end of the bar 18, thereby locking the anchoring arms in their outstretched operative positions. With the spike locked in the tie, it will be impossible to withdraw or loosen the same without first releasing the bolt 25 by exerting an outward pressure upon the spring 26 which moves the bolt 25 from engagement with the bar 18 and after which release of the bar 18, the spike may be 105 110

withdrawn, which action forces the arms 18 to return to their seated positions within the slot 15 inoperatively closed until again forced outwardly. A serviceable spike is 5 thus provided readily locked to the work although easily withdrawn when desired and while the present form of the same is believed to be preferred, minor changes may be made without departing from the spirit 10 and scope of the invention as claimed.

What I claim as new is:—

A railway spike comprising a shaft having a head at one end and a V-shaped point at its opposite end, the said shaft having 15 an axial bore therethrough and a transverse slot communicating with the said bore and having downwardly converging faces paral-

lel with the outer sides of the said shaft point, anchoring arms having outer sharpened edges pivoted within the said slot, an 20 operating bar longitudinally shiftable within the said bore having geared connections with the said arms, the shaft head having an opening therethrough communicating with the said bore, a bolt slidably arranged within 25 in the said opening having a path of movement inwardly of the said bore and outwardly of the free end of the said bar when the arms are in their operative position, and a retractable spring operating means for 30 the said bolt.

In testimony whereof I affix my signature.

STEPHEN OBEDA.
